Application September 3, 1935, Serial No. 38,904

10 Claims. (Cl. 139—33)

This invention relates generally to weaving and particularly to simplified weaving apparatus and processes by which various types of fabric and woven articles may be conveniently and expeditiously woven so that the process and apparatus of this invention are particularly suitable for homecraft.

Although weaving has heretofore been practiced on a limited scale as homecraft, the looms heretofore employed for that purpose have ordinarily been of large and inconvenient size and considerable skill is necessary in the operation thereof, particularly in the threading of the heddles which have been universally employed.

15 The present invention, although particularly adaptable for homecraft use because of its simplified character and the fact that devices made in accordance with the present invention can be of relatively small size or any desired size, further 20 contemplates novelties adaptable to looms generally.

The object of the present invention, generally stated, is to provide weaving apparatus wherein the use of heddles is dispensed with.

25 A further object is to provide a weaving apparatus and process wherein the weft or filler is woven upon a warp of resilient material which warp is later to be removed.

Another object of this invention is to provide 30 a weaving apparatus and process which, although simple in form, is adaptable to the weaving of patterns and novelty designs.

Other objects of this invention will become apparent upon reading the following description 35 in this connection with the accompanying drawing, in which

Figure 1 is a perspective view of one embodiment of the weaving apparatus constructed in accordance with the present invention showing 40 the relation of the weft or filler to the resilient warp;

Figure 2 is a view in end elevation showing the apparatus of Figure 1 in the relative positions occupied when sheds are formed;

45 Figure 3 is a view in end elevation showing another embodiment of the weaving apparatus having another type of shedding means;

Figure 4 is a plan view of the apparatus shown 50 in Figure 3;

Figure 5 is a detail view of the cam employed in the apparatus of Figure 3;

Figure 6 is a detail view showing the manner in which the resilient warp supports the textile 55 warp;

Figure 7 is a plan view showing another embodiment of the shedding device.

In accordance with the present invention, generally stated, weaving apparatus is provided in which spreading of the warp to permit insertion 5 of the weft or filler strand is accomplished without the use of heddles and, in the various embodiments, by apparatus which moves the respective warps against a tension out of the position normally occupied by them in order to produce a 10 shed. A series of cams arranged upon a shaft so as to be rotated together, but mounted so as to be relatively adjustable, is an advantageous device for accomplishing this result.

In accordance with one aspect of the present 15 invention the weft or filler strand of the material being woven is applied to a warp of resilient material, such as wire or rods with which the permanent textile warp is associated. This resilient warp possesses a sufficient stiffness to permit the same to be supported in cantilever manner at one end leaving the other ends free for manipulation. The various groups of resilient warp rods may be moved out of alignment with each other in order to produce sheds in the manner desired and, when thus disaligned, the filler strand may be laid in the open shed and compacted into place.

After the desired length of material has been formed the resilient warp may be removed. 30 When the resilient warp is removed, the textile warp strand, which was held in position by the resilient warp during the application of the weft, remains and hence the textile fabric remains intact.

One illustrative embodiment of the present 35 invention is shown in Figures 1 and 2. In accordance with this invention a series of resilient warp rods 1, 2, 11, 12, 21, 22, 31, 32, 41, 42 are secured in cantilever relation in a suitable base 40 block 3. The resilient warp rod is illustrated in detail in Figure 6. The rod 1 has its upper end 206 bifurcated so as to adapt the rod to receive a textile warp strand 207 therein. When in position for operation the textile warp strand 207 45 extends alongside each of the warp rods and may either be knotted or otherwise secured to the top thereof, or may extend up and back having both ends secured in base block 3. In the latter case it is evident that a double textile warp is provided. This arrangement provides a temporary 50 resilient warp associated with a permanent textile warp. Then the weft or filler is applied upon this composite warp.

It will be observed from Figure 1 that rods 1, 55

11, 21, 31 and 41 are shorter than the rods 2, 12, 22, 32, and 42 and that the upper ends of the former are free, whereas the upper ends of the latter are connected to a block 5. Also connecting the block 5 to the base block 3 is a pair of bars 6 arranged one at each end of the respective blocks. The bar 6 may also be made of flat resilient material so as to remain stiff in the plane of the rods 2, 12, but permit bowing thereof in a 10 plane at right angles thereto.

Blocks 3 and 5 are, as shown, composed of complementary parts between which the ends of rods 1, 2, 11, 12, etc. as well as bars 6 may be clamped. In order to permit adjustment of the relative positions of bars 1, 2, etc., or the spacing therebetween in accordance with the weaving desired, the complementary parts in blocks 3 and 5 may be provided with a plurality of notches spaced as close together as possible in order to provide a large 20 number of variations in the spacing of the rods. As an alternative, however, the complementary parts of blocks 3 and 5 may be provided with a groove lined with a yieldable material, such as a film of sponge rubber, in order to securely grip 25 the ends of the rods and clamp them together.

The base block 3 may be suitably mounted so as to rock or oscillate upon a base 7 which may be provided with suitable means for limiting the rocking movement of the base block.

30 When the base block 3 with its adjunct rods is rocked to the position illustrated in full lines in Figure 2, it will be observed that resilient warp rods extend not perpendicular, but angularly, so that the weight of the block 5 on the outer ends 35 of rods 2, 12, etc. causes a bowing of those rods as well as bars 6, however leaving rods 1, 11, etc. substantially straight as shown. This provides an open shed 8 between the respective series of rods into which a textile strand or thread 9 may 40 be laid or applied. It will be understood, of course, that in the first application of strand 9 the same will be tied to one or the other of end bars 6. Strand 9 may then be pressed home into 45 the position against base block 3 or preceding filler strands. This operation may be carried out conveniently in small devices by means of the fingers but it is obvious that a suitable combing device or reed may be employed for this purpose.

After the strand 9 has been compressed into 50 proper position base block 3 with its adjunct parts may be rocked to the dotted line position shown in Figure 2 whereat the weight of block 5 will cause rods 2, 12, etc. to bow in the opposite direction from the previous one and produce an 55 opposite shed 10. After being passed around end bar 6, filler strand 9 may be returned through shed 10 so as to produce the next shot of the fabric. This process of inserting shots of filler strand through the open sheds formed by bending of the rods 2, 12, etc., alternately in opposite directions may then be continued until the desired length of material is obtained.

While, in order to simplify the disclosure in the description and in the accompanying drawing the apparatus of this invention has been 65 illustrated as provided with only ten temporary warp rods, it will be understood that any desired number may be employed.

After the desired number of shots of filler material has been laid or applied so as to produce 70 the desired length of fabric, the material, consisting of filler 9 on the composite warp is removed from blocks 3 and 5 ready to have the temporary warp rods 1, 2, etc. removed therefrom. 75 To accomplish this, such knots or connections,

as were initially made to hold the textile warp strands 207 in proper aligned relation with the respective warp rods, are released. The resilient temporary warp rods may then be withdrawn from the fabric, leaving the permanent textile 5 warp in position therein.

If it is desired to reload the apparatus so as to secure a greater length of piece, the temporary warp rods may be removed from all but a few of the last applied shots of filler or weft 9. The latter may be left upon the warp rods, and the rods reinserted in the blocks 3 and 5 so that the weaving operation may be resumed to secure the desired length.

In case it is desired to produce a fabric of 15 greater width than one loading of the apparatus will provide for, individual strands of filler instead of a continuous one, as hereinbefore described, may be employed for each shot. This will leave the ends of the filler strands free at 20 one side of the material. All but the last few resilient warp rods, most remote from the finished edge may be removed. The material may then be reinserted into the device with the group of unremoved warp rods positioned at the opposite end 25 of block 3 from before. The loose ends of the individual filler strands may then be woven upon the rods which had been removed from the first block of fabric and reinserted in block 3 beyond the unremoved rods. This process can, of course, 30 be repeated as many times as is necessary in order to secure the desired width.

When the double textile warp, as above suggested, is utilized and when it is desired to produce a piece of fabric of greater length than is possible with one loading of the loom, it is apparent that excess length of warp may be provided on each rod and the end thereof suitably accommodated adjacent block 3. When the device is once loaded, therefore, the temporary warp 40 rods may be removed and one strand of the permanent double warp pulled through the fabric already woven to an extent sufficient to permit insertion of the temporary warp rods. The warp rods will be inserted relatively close to the fabric 45 already produced at their lower ends and successive filler or weft strands then inserted, as hereinbefore described, so as to produce a continuation of the fabric already woven.

Referring now particularly to Figures 3 and 4 50 another embodiment is shown wherein the resilient warp rods 101, 102, 111, 112, 121, 122, 131, 132, 141, and 142 corresponding respectively to the warp rods, similarly numbered less a hundred in the previous embodiment, are all left free 55 at their upper ends while the lower ends are clamped in a base block 3 as before. In accordance with this embodiment, however, the base block 3 is arranged to be securely clamped to a suitable base 70. Supported adjacent the upper 60 ends of warp rods 101, 102, etc. is a series of cams 201, 202, 211, 212, 221, 222, 231, 232, 241, and 242, cooperating one with each warp rod. These cams which operate to force selected warp rods out of alignment with the others and thereby to 65 produce a shed may be of any desired shape, such as that shown in Figure 5. The entire series of cams may be mounted upon a shaft 100 which is provided with suitable means for clamping the same against displacement but, nevertheless, permitting relative adjustment of the cams. This may be accomplished by providing a plurality of splines on shaft 100 for cooperating with grooves in the respective cams, but for the purpose of 70 small devices, as will be employed in homecraft, 75

sufficiently positive clamping of the cams in position may be accomplished by compression of the same between a nut threaded to the shaft and a suitable abutment.

5 Similar cams may also be provided for end bars 6, but as shown in the accompanying drawing, end bars 6 are seated against discs 60, the throw of which is only one-half of the throw of the perspective cams 201, 202, etc. Hence bars 6
10 are maintained in an intermediate position so as to be conveniently located for passing the weft or filler strand therearound, regardless of the position of the adjacent warp rods.

Accordingly, one end of shaft 100 may be provided with a suitable knob 103 which, in addition to operating as a manipulating means, also provides an abutment against which the series of cams may be clamped. The other end of rod 100 may be threaded so as to receive a wing nut 104. 15 Cams 101, 102, etc. are, therefore, placed upon shaft 100 between knob 103 and wing nut 104 and intermediate the respective cams, it is advantageous to provide guide discs 105 which extend radially from the shaft at least as far as cams 201, 202, etc. and thus maintain warp rods 101, 102, etc. in proper relative position. To this extent discs 105 will be understood as performing a function analogous to that of the raddle of the conventional loom. For convenience in assembly of 20 each of the cams 201, 202, etc. may be secured to a guide disc 105 or in fact may be secured between two such guiding discs. However, in order to permit flexibility of the device and adapt it to weaving of many different patterns so in fact that 25 it may be converted in effect from a two harness loom to a four, six, etc. harness loom, the individual cams 101, 102, etc. should be left independent of each other for relative phase adjustment on shaft 100. For instance, if only two 30 relative positions are occupied by cams 101, 102, etc. that is to say, for example, the odd numbered cams are displaced 90° from the even numbered cams, the equivalent of a two harness loom will be presented. On the other hand, if the 35 cams are occupying four relative positions and are disposed, for instance, in 90° phase displacement so that there is for example 90° between cams 101 and 102, 180° between cams 101 and 111, and 180° between cams 102 and 112, then it is apparent 40 that the equivalent of a four harness loom is presented. Likewise, if the cams are arranged in 60° phase displacement, then the equivalent of a six harness loom is presented, etc.

In order to permit variation in the spacing of 45 rods 101, 102, 111, etc., it may be convenient to mount each of the corresponding cams between guide discs, that is to say, a guide disc on each side of each cam. When this is done, spacing discs or washers may be interposed between guides 50 for adjacent rods and thus adapt the device to variable spacing of the rods without necessitating different cams for each variation.

Instead of forming cams 201, 202, etc., as individual elements, lugs may be upset or otherwise 55 suitably formed upon the respective guide discs 105 and so arranged that when the discs are rotated to the selected position, they will operate to lift the warp rods as above described with reference to the cams.

60 In the operation of this embodiment it will be apparent that when knob 103 is turned so as to bring the point 210 of cam 201 into contact with warp rod 101 that warp rod will be forced out of alinement with those warp rods which are contacting portion 220 of their respective cams, and

hence a shed is produced into which the filler strand may be inserted as described with reference to the previous embodiment. After this filler strand is inserted knob 103 may be turned to bring other warp rods forward and produce the shed 5 desired for the next shot. In this connection it may be pointed out that the maximum possible displacement of the respective warp rods is not necessarily availed of in producing the shed, but it will be evident to those skilled in the art that 10 for the production of some patterns the same warp rod will be displaced forward on two or more successive shots. For instance, as shown in Figure 3 (where the cams are illustrated in 90° displacement—four relative positions) both cams 15 201 and 202 are operative to force their respective rods 101 and 102 forwardly. Now if the knob 103 is rotated 90° further in a clockwise direction it will be apparent that while rod 101 will recede, rod 102 will remain displaced forward and rod 111 20 through the action of cam 211 will be forced into alinement with rod 102.

It will be understood that in the embodiment shown in Figures 3 and 4 base block 3 is so positioned that rods 101, 102, etc. are biased with 25 some tension against their respective cams even when in their receded positions (but in contact with portions 220 of the cams). When the apparatus is loaded, however, the presence of the filler material between the respective warp rods sometimes tends to reduce the tension with which the rods bear against their cams. In order to assure that the rods will be maintained in positive contact with their respective cams the series of cams on the cam shaft 100 may be arranged for 30 adjustment normal to the series of rods. In order to accomplish this shaft 100 with its series of cams may be mounted on a pair of arms 115 which are in turn carried by standards 200. Arms 115 35 may be seated in suitable guide slots in standard 40 200 or upon rails secured thereto and provided with a pin and slot connection 116 so as to permit adjustment outwardly against the tension of rods 101, 102, etc.

When heavy materials are being employed for 45 the filler strand it frequently happens that the tension of the temporary warp rods against their respective cams will become reduced due to distortion of the rods and in order to overcome such distortion a suitable stirrup 205 may be provided. 50 Such a stirrup may consist of a rod extending across in front of the series of rods 101, 102, etc. and adjustably connected to the standards 200.

Where plain weaving only is to be done upon the apparatus of Figures 3 and 4 the cams may 55 be dispensed with and simpler means provided for accomplishing the desired shedding of the resilient warp rods. Such a means may consist of a bar of such length as to span the selected series of warp rods whereby a bending force may 60 be concurrently applied to a plurality of rods without disturbing the position of rods not in contact with the bar. For example, a bar 250, as shown in Figure 7, may be provided with a series of dents 251 which dents are spaced apart 65 at double the spacing of warp rods 101, 102, etc. Bar 250 may be arranged to slide back and forth on a suitable guide plate 252 carried by standard 200. Guide plate 252 may be provided with a series of dents 253, one for each temporary warp 70 rod so as to maintain the same separate. As is apparent from Figure 7, when the bar is in the position illustrated, the odd numbered rods 101, 111, etc. will be forced forwardly while the even numbered rods 102, 112, 122, etc. will occupy the 75

dents so that a displacement of the rods is achieved, producing a shed. It will be understood, of course, that suitable means may be provided for locking bar 250 in the shed producing 5 position while the filler strand is inserted. After the filler strand is inserted in the shed thus provided the lock may be released and bar 250 moved backwardly so as to permit the odd numbered rods 101, 111, etc. to aline themselves with the 10 others. The bar 250 may be moved one space (the distance between the adjacent warp rods) either to the right or to the left to bring the dents in alinement with the odd numbered rods 101, 111, etc. Now if rod 250 is moved forwardly as 15 before, it is evident that the opposite shed will be produced.

Of course, in the use of this embodiment, as in the others, the successive shots of weft or filler strands are made through alternate sheds, and 20 after the composite warp is loaded to the desired extent, the temporary resilient warp rods are removed, leaving the textile warp in place.

From the foregoing description it is apparent that the present invention accomplishes its 25 objects and that novel weaving apparatus and process as well as novel resulting fabric is provided. It is apparent that many modifications of the process, apparatus and fabric hereinbefore described will present themselves to those skilled 30 in the art without departing from the spirit of this invention. It is to be distinctly understood, therefore, that such modifications and the use of such individual features and sub-combinations of features as do not depart from the spirit of this 35 invention are, although not specifically defined herein, contemplated by and within the scope of the appended claims.

Having thus described the invention, what is 40 claimed is:

1. Weaving apparatus comprising, a base, a series of resilient rods connected in cantilever relation to said base, and a series of cams arranged respectively to cooperate with the rods for shedding the same.

2. In the art of weaving fabrics the process comprising, forming a temporary resilient warp, supporting a textile warp upon the resilient warp, bending selected elements of the resilient warp to form a shed, inserting filler strands through 50 the shed upon the composite warp, and thereafter removing the temporary resilient warp.

3. In the art of weaving fabrics the process comprising, forming a temporary resilient warp by clamping temporary resilient warp elements 55 together at one end thereof with the opposite ends of the elements free for relative movement, connecting a textile warp strand at the free end of each of said elements, holding each textile warp strand in substantial alinement with the element to which it is connected, bending the 60 selected elements of the resilient warp to form a shed, inserting filler strands in the composite warp, and thereafter removing the temporary resilient warp elements.

4. Weaving apparatus comprising a base, a series of resilient rods connected in cantilever relation to said base, a shaft extending laterally across said series of rods adjacent the free ends thereof, and a series of cams mounted upon said 70 shaft and arranged for relative phase adjustment

thereon, said cams cooperating respectively with said rods.

5. Weaving apparatus comprising, a series of resilient rods arranged to constitute a temporary warp, alternate rods being longer than the intervening rods, said rods provided with means for holding a permanent textile warp in alinement therewith, and means for supporting the longer rods at one end thereof in cantilever relation so as to permit bending thereof relative to the intervening rods to form sheds. 10

6. Weaving apparatus comprising, a series of resilient rods arranged to constitute a temporary warp, said rods provided with means for holding a permanent textile warp in alinement therewith, and means for concurrently bending a plurality of selected rods relative to and independently of other rods so as to form sheds for the insertion of substantially straight textile filler strands. 15

7. Weaving apparatus comprising, a base, a series of resilient rods connected in cantilever relation to said base and being free for relative bending to form sheds, said rods being of circular section whereby they may be flexed in any direction, means for concurrently bending a plurality of selected rods relative to and independent of other rods so as to form sheds, and means on each of said rods for holding a textile strand in alinement therewith during weaving. 20

8. In the art of weaving fabric the process comprising forming a temporary warp of metallic rods, alternate warp rods being longer than the intervening rods, supporting a textile warp upon each of said warp rods, bending the longer warp rods relative to the shorter warp rods to form a 25 shed, inserting filler strands through the shed upon the composite warp, and removing the temporary warp.

9. In the art of weaving fabrics the process comprising, forming a temporary resilient warp 30 by clamping temporary resilient warp elements together at one end thereof with the opposite ends of the elements free for relative movement, some of said warp elements being longer than others, connecting a textile warp strand at the free end of each of said elements, holding each textile warp strand in substantial alinement with the element to which it is connected, bending the longer warp elements relative to the shorter warp elements to form a shed, inserting filler strands 35 in the composite warp, and thereafter removing the temporary resilient warp elements. 40

10. Weaving apparatus comprising, in combination, a series of resilient temporary warp rods, said rods being sufficiently resilient to permit, without exceeding their elastic limit, an amplitude of bending to provide a space for the insertion of a substantially straight weft strand between the bent and unbent rods, means on each of the rods for holding permanent textile warp in alinement therewith, means for supporting said rods in cantilever relation so that ends of the rods remote from the supporting means are freely relatively movable, said apparatus being free of obstructions which would prevent substantially straight weft strands from being laid in an open shed between bent and unbent warp rods. 45 50 55 60 65
